(57) **CLAIM**

The ornamental design for a chicken coop door, as shown and described.

DESCRIPTION

FIG. 1 is a top perspective view of a chicken coop door showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view of the chicken coop door of FIG. 1, shown in a second configuration with the door open in an environment of use.

The broken lines showing of chickens, and elements attached to the door in FIG. 8 depict environmental subject matter and forms no part of the claimed design. All remaining broken lines in FIGS. 1-8 depict portions of the chicken coop door that form no part of the claimed design.
